UNITED STATES PATENT OFFICE

98,671

DESIGN FOR A TEXTILE FABRIC

August Hafner, Flushing, N. Y.

Application August 27, 1935, Serial No. 58,328

Term of patent 3½ years

To all whom it may concern:

Be it known that I, August Hafner, a citizen of the United States of America, residing at Flushing, Long Island, county of Queens, State of New York, have invented a new, original, and ornamental Design for a Textile Fabric, for which the following is a specification, reference being had to the accompanying drawing, forming part thereof, wherein,

The figure is a plan view of a textile fabric showing my new design.

The fabric has a fine weave, open mesh background on which are interspaced raised or embossed motifs.

I claim:

The ornamental design for a textile fabric substantially as shown and described.

AUGUST HAFNER.
